UNITED STATES PATENT OFFICE.

HARRY R. WALKER, OF ST. LOUIS, MISSOURI.

OIL BURNER.

Application filed January 26, 1925. Serial No. 4,737.

This invention relates to improvements in oil burners, and consists in the novel construction hereinafter disclosed.

An object of the invention is to provide, in association with a fire pot and an oil chamber with a system of oil feed therefor, a device for atomizing the oil.

Another object of the invention is to provide an oil burner having a rotor device for atomizing the oil and delivering the same from an oil chamber to a fire pot, with provision for supplying the oil from a source of supply, together with means for furnishing a supply of air to complete combustion of the atomizer oil delivered to the fire pot.

Additional advantages of the construction will be apparent from the following detailed description thereof, taken in connection with the accompanying drawings, in which

Fig. 1 is a plan view of the apparatus.

Fig. 2 is a side elevation.

Fig. 3 is a side elevation showing the burner structure in section.

Fig. 4 is an enlarged vertical section through the burner.

Fig. 5 is a vertical section taken substantially on the line 5—5 of Fig. 4.

As illustrated in the drawings the burner proper includes a fire pot 1 arranged on suitable supports 2 for mounting within the combustion chamber of a heating element. The fire pot includes a bowl-shaped casting 3 and a lining member 4, the member 4 having an inverted truncated conical wall 5 and a horizontal flange 6 that fits over and rests upon the upper edge of the casting 3. The lower edge of the wall 5 terminates above the bottom wall of the casting 3, leaving an air space between the lower edge of the wall 5 and the bottom of the casting 3. The bottom wall of the casting 3 has an axial opening, and arranged beneath the opening is a semi-cylindrical casting 7 constituting an oil chamber. At the sides of the casting 7, and at right angles to the axis thereof said casting carries integral extensions 8 forming chambers 9 running parallel with the axis of the casting 7.

The space between the inner face of the casting 3 and the inner face of the wall 5 forms a circular chamber 10 and between the chamber 10 and each of the chambers 9 there are openings 11 forming means of communication between the chamber 10 and the chambers 9. The walls between the chambers 9 and the interior of the casting 7 have open-

ings 12 constituting passageways from the chambers 9 to the interior of the chamber formed by the casting 7.

At the bottom of the casting 7 is a screw plug 13 for draining and cleaning out the chamber formed by said casting, and in the outer end wall of said casting is a screw plug 14 so that access may be had to the interior of the chamber formed by the casting.

Matched against the face of the opposite end wall of the casting 7 is a cylindrical member 15 that constitutes an oil delivery passage to the chamber formed by the casting 7 and that also supports bearings 16. A shaft 17 extends inwardly through the member 15 and into the chamber formed by the casting 7 and supports at its inner end a rotor that includes a solid cylindrical hub 18 having integrally formed radial ribs 19 arranged at spaced intervals, thereby forming therebetween parallel series of grooves. The edges of the ribs 19 are preferably knurled or roughened.

The rotor is rigidly supported by the shaft 17 which passes through the axis of the hub 18 and held in place by a nut 20 having threaded engagement with the end of the shaft 17. Access to the nut for mounting the rotor upon the shaft may be had through the opening in which the screw plug 14 is mounted. The extreme diameter of the rotor is such that when mounted axially of the casting 7 the lower edge of the rotor will extend to a point adjacent to the bottom of the casting and the upper edge of the rotor will extend above the lower edge of the wall 5.

The oil entering the member 15 is delivered inwardly to the chamber formed by the casting 7 and serves also to lubricate the bearings 16 for the shaft 17. The outer end of the member 15 is provided with a stuffing box 21 to prevent the passage of oil outwardly through the end of said member or around the shaft 17 that extends therethrough.

The oil delivery system for supplying oil to the oil chamber of the burner includes an oil-supply pipe 22 connected with any suitable source of supply, the supply pipe 22 leading to an oil pump 23 of any desired design or type. A pipe 24 extends from the oil pump and is connected with a pipe 25 by a T-fitting 26, the pipe 25 extending forwardly from its connection with the pipe 24 and by means of a right angled connection

27 connects into the side wall of the member 15.

The pipe 25 is equipped with a control valve 28 preferably of the dial control type 5 so as to regulate the passage of oil therethrough to the oil chamber. An oil pressure gage 29 may be inserted in the line between the dial control valve 28 and the delivery pipe from the pump. During the normal functioning of the device a constant supply of oil under regulated pressure is delivered to the member 15 through which it flows inwardly to the oil chamber.

The oil chamber is provided with an oil 15 overflow pipe 30 that is connected into the side of the casting 7 at the level of the axis of the member 15. Thus a constant feed of oil to the oil chamber maintains an oil level slightly below the opening into the overflow pipe, because of the fact that the delivery opening to the oil chamber is on a plane slightly lower than the lower edge of the opening into the overflow pipe. In normal operation the shaft 17 is rotated at a 20 relatively high rate of speed causing the rotor to revolve in the oil chamber and, by centrifugal action of the ribs of the rotor operating in the body of oil, divides the oil into small particles thoroughly atomizing it 25 and delivering it into the fire pot, where it is mixed with air, as will be hereinafter described, and burned. Due to the agitating action of the rotor any grade of fuel oil may be utilized in the burner and produce efficient 30 results.

If, for any reason, the consumption of oil from the oil chamber is not maintained, or an over supply of oil be delivered to the oil chamber, the level of oil will rise to a point 40 where it will overflow into the passage 30, the end of the passage 30 being arranged to discharge into a bucket 31 carried by a lever 32 of an automatic drip valve 33 interposed in the pipe 25. The valve 33 is of known 45 construction and is designed to operate to close the passage 25 when a predetermined quantity of oil has discharged from the overflow pipe 30, thus shutting off the delivery of oil to the oil chamber. When this occurs, 50 by reason of the continued action of the oil pump, a back pressure will be built up in the passage 25 against the closed valve 33 and will be carried away from the system and back to the source of supply through a pipe 55 34 connected into the T-fitting 26 when the pressure operating valve 35 is opened. The valve 35 is of known type, commonly called a pressure reducer valve, and is designed to open and permit the back flow through the 60 pipe 34 when a predetermined back pressure is built up after the valve 33 is closed.

The system for delivering air to the fire pot includes a blower 36 and an air conduit 37 that extends from the blower forwardly 65 and enters through the wall of the casting

3 and into the chamber 10. A portion of the air pressure delivered to the chamber 10 passes across the bottom of the fire pot into the space between the lower edge of the wall 5 and the bottom of the casting 3, and a 70 part of the air is by-passed downwardly through the openings 11 into the chambers 9 and across the oil chamber as it is emitted from the openings 12, the openings 12 being at an elevation slightly above the normal 75 level of oil maintained in the oil chamber.

The arrangement, thus described, for delivery of air provides efficient means for thoroughly mixing the atomized oil with air, forming a highly combustible mixture 80 that develops a high heat and results in substantially complete combustion of the fuel.

It will be noted that the shaft 17 constitutes a power shaft for driving the rotor of the pump, the rotor of the blower and the rotor for atomizing the oil, the axes of said rotors being arranged in alinement and the shaft 17 extending axially thereof so that the whole apparatus may be driven 85 from a common source of power such, for instance, as a motor M arranged at and connected with the outer end of the shaft 17.

I am aware that the invention may be modified in numerous details without departing 90 from the spirit and scope thereof. I do not limit myself unessentially, therefore, to the detailed construction shown and described but contemplate such variations as may be within the scope of the appended 95 claims.

What I claim and desire to secure by Letters Patent is:—

1. An oil burner comprising an oil chamber, a fire pot above and opening into said chamber, a wall within the fire pot having its lower edge above the bottom of the fire pot, a rotor in said chamber having its periphery above the plane of the lower edge of said wall in the fire pot, means for admitting air 105 between said wall and the wall of the fire pot, and means for conducting air into said chamber.

2. An oil burner comprising an oil chamber, a fire pot opening into the oil chamber, a 110 rotor in the oil chamber having its upper side extending into the fire pot, an inclined wall in the fire pot and spaced from the wall of the fire pot, means for admitting air into the space between the wall of the fire pot 115 and said inclined wall, and means for conducting the air from said space into the oil chamber.

3. An oil burner comprising a fire pot having a side wall and a bottom wall, an oil 120 chamber below and opening through the bottom wall of the fire pot, a rotor mounted on a horizontal axis in said chamber, a series of circumferential ribs on the rotor extending upwardly into the fire pot, means form- 125

- ing an air space in the fire pot, and means for conducting air from said space into said chamber.
4. An oil burner comprising an oil chamber, a fire pot above and opening into said chamber, a wall within the fire pot having its lower edge above the bottom of the fire pot, a rotor in said chamber having its periphery above the plane of the lower edge of said wall in the fire pot, means for admitting air between said wall and the wall of the fire pot, means for conducting air into said chamber, and means for maintaining an approximately uniform quantity of oil in said chamber.
5. An oil burner comprising an oil chamber, a fire pot opening into the oil chamber, a rotor in the oil chamber having its upper side extending into the fire pot, an inclined wall in the fire pot and spaced from the wall of the fire pot, means for admitting air into the space between the wall of the fire pot and said inclined wall, means for conducting the air from said space into the oil chamber, and means for maintaining an approximately uniform quantity of oil in said chamber.
6. An oil burner comprising a fire pot having a side wall and a bottom wall, an oil chamber below and opening through the bottom wall of the fire pot, a rotor mounted on a horizontal axis in said chamber, a series of circumferential ribs on the rotor extending upwardly into the fire pot, means forming an air space in the fire pot, means for conducting air from said space into said chamber, and means for maintaining an approximately uniform quantity of oil in said chamber.
7. An oil burner comprising an oil chamber, a fire pot above and opening into said chamber, a wall within the fire pot having its lower edge above the bottom of the fire pot, a rotor in said chamber having its periphery above the plane of the lower edge of said wall in the fire pot, means for admitting air between said wall and the wall of the fire pot, means for conducting air into the space between the wall of the fire pot and said inclined wall, means for admitting air between said wall and the wall of the fire pot, means for conducting air into said chamber, a pipe for conducting oil into said chamber, and a pipe for conducting oil from said chamber to prevent an accumulation of an excess amount of oil in said chamber.
8. An oil burner comprising an oil chamber, a fire pot opening into the oil chamber, a rotor in the oil chamber having its upper side extending into the fire pot, an inclined wall in the fire pot and spaced from the wall of the fire pot, means for admitting air into the space between the wall of the fire pot and said inclined wall, means for conducting the air from said space into the oil chamber, a pipe for conducting oil into said chamber, a pipe for conducting oil from said chamber to prevent an accumulation of an excess amount of oil in said chamber, and means operated by the oil passing from said second pipe to prevent flow of oil through said first pipe.
9. An oil burner comprising a fire pot having a side wall and a bottom wall, an oil chamber below and opening through the bottom wall of the fire pot, a rotor mounted on a horizontal axis in said chamber, a series of circumferential ribs on the rotor extending upwardly into the fire pot, means forming an air space in the fire pot, means for conducting air from said space into said chamber; a pipe for conducting oil into said chamber, and a pipe for conducting oil from said chamber to prevent an accumulation of an excess amount of oil in said chamber.
10. An oil burner comprising an oil chamber, a fire pot above and opening into said chamber, a wall within the fire pot having its lower edge above the bottom of the fire pot, a rotor in said chamber having its periphery above the plane of the lower edge of said wall in the fire pot, means for admitting air between said wall and the wall of the fire pot, means for conducting air into said chamber, a pipe for conducting oil into said chamber, a pipe for conducting oil from said chamber to prevent an accumulation of an excess amount of oil in said chamber.
11. An oil burner comprising an oil chamber, a fire pot opening into the oil chamber, a rotor in the oil chamber having its upper side extending into the fire pot, an inclined wall in the fire pot and spaced from the wall of the fire pot, means for admitting air into the space between the wall of the fire pot and said inclined wall, means for conducting the air from said space into the oil chamber, a pipe for conducting oil into said chamber, a pipe for conducting oil from said chamber to prevent an accumulation of an excess amount of oil in said chamber, and means operated by the oil passing from said second pipe to prevent flow of oil through said first pipe.
12. An oil burner comprising a fire pot having a side wall and a bottom wall, an oil chamber below and opening through the bottom wall of the fire pot, a rotor mounted on a horizontal axis in said chamber, a series of circumferential ribs on the rotor extending upwardly into the fire pot, means forming an air space in the fire pot, means for conducting air from said space into said chamber; a pipe for conducting oil into said chamber, a pipe for conducting oil from said chamber to prevent an accumulation of an excess amount of oil in said chamber, and means operated by the oil passing from said second pipe to prevent flow of oil through said first pipe.
